UNITED STATES PATENT OFFICE.

ROBERT P. GREENLEAF, OF SHAKER HEIGHTS, OHIO, ASSIGNOR TO FRANK BILLINGS,
OF CLEVELAND, OHIO.

LOADING MACHINE.

Application filed January 23, 1924. Serial No. 687,897.

To all whom it may concern:

Be it known that I, ROBERT P. GREENLEAF, a citizen of the United States, residing at Shaker Heights, in the county of Cuyahoga and State of Ohio, have invented a certain new and useful Improvement in Loading Machines, of which the following is a full, clear, and exact description.

This invention relates to a loading machine of the general type having a digging member supported on a superstructure which can be revolved to swing the loaded dipper or shovel for discharging the material into cars or the like located either at the side or the rear of the machine.

The principal object of the invention is to provide an efficient loading machine of this type, and one which can be easily and conveniently operated either in a narrow space such as a mine drift or tunnel, or for ordinary out-of-door excavating work.

A further and more specific object is to provide improved means for supporting and operating the digging member, it being a feature of the present machine that the superstructure can be revolved with the digging member at dumping height and extended laterally from the machine for use in the open or in a wide enclosed space, or compactly folded in over the machine to permit the superstructure to be revolved in a narrow space.

A still further object is to provide power mechanism for operating the digging member and for revolving the superstructure of the machine and for propelling the machine over the ground, such that the features of simplicity of construction and ease of control are realized to a high degree.

The invention may be briefly summarized as consisting in certain novel details of construction, and combinations and arrangements of parts which will be described in the specification and pointed out in the appended claims.

In the accompanying sheets of drawings illustrating the invention, Fig. 1 is a side view of the machine with the dipper shown in full lines swung in over the machine substantially within the confines of the outline of the superstructure frame and showing by dotted lines the dipper and its supporting arms in various positions; Fig. 2 is an end view looking toward the left

of Fig. 1; Fig. 3 is a plan view with the cover removed, which normally houses the operating mechanism; Fig. 4 is a vertical sectional view through the superstructure substantially along the line 4-4 of Fig. 3, looking in the direction indicated by the arrows; Fig. 5 is a transverse sectional view through the superstructure and truck, substantially along the line 5-5 of Fig. 3, looking in the direction indicated by the arrows; Fig. 6 is a vertical sectional view through the superstructure and truck, with parts in elevation, substantially along the line 6-6 of Fig. 3, looking in the direction indicated by the arrows; Fig. 7 is a view partly in section and partly in side elevation showing the turn-table support and part of the mechanism utilized for causing the operating motor to revolve the superstructure, or for propelling the machine as a whole over the ground; and Fig. 8 is a partial plan view of the same, omitting, however, the turn-table.

The superstructure of the machine includes a rotary frame or turn-table 10 and a truck designed to travel over the ground, which truck in this instance includes a frame 11 equipped with ground engaging members 12 of the caterpillar or endless belt type, though the truck frame may, if desired, be equipped with ordinary ground or track wheels. The frame of the truck carries a turn-table ring 13 on which the turn-table, and, in fact, the entire superstructure is supported through the medium of an annular series of rollers 14, the superstructure being designed to turn about the axis of a short vertical shaft 15 (see Figs. 5 and 6) which extend down from the turn-table centrally through the fixed turn-table ring 13. The turn-table includes in addition to the base or bottom portion, a pair of upwardly extending side housings 10^a which together with a cover 16 enclose the operating mechanism.

The digging member consists of a shovel or dipper 17, with a swinging bottom 18, normally held closed by a latch 19^a which can be pulled with a cord or cable so as to release the bottom and permit the weight of the material to swing the bottom downwardly and rearwardly for dumping. The bottom is designed to be latched automatically in the well-known way.

The dipper has attached to it a pair of dipper arms 19 which are pivoted at 20 to the outer ends of a pair of dipper swinging arms 21, whose inner ends are secured to the 5 end of a shaft 22 suitably journaled in the forward portions of the side housings 10^a of the turn-table. The dipper arms may be swung independently of the arms 21, and to accomplish this they are provided with extensions 23 extending inwardly or rearwardly beyond the pivots 20, these extensions being provided with grooved peripheral portions shaped to a suitable curve which may or may not be arc-shaped and 10 adapted to receive cables 24 arranged to be wound onto and unwound from a pair of drums 25 located at the outer sides of the housings 10^a and secured to a drum shaft 26 also journaled in the housings 10^a a distance 15 to the rear of shaft 22, to which are attached the dipper swinging arms 21. It is an important feature of this construction that the power is applied to swing the arms 21 and to swing the arms 19 from two separate 20 shafts whose axes are displaced, as shown in the drawings, and there is a relation between the spacing shafts 22 and 26 and the radius of the grooved dipper arm extensions 23, this relation being such that 25 there is substantially a parallelogram arrangement between arms 21 and the cables 24, which is important in the operation of the machine, particularly when the elevated dipper is being swung from extended position 30 to retracted position or vice versa.

It might be here stated that in Fig. 1, position A may be assumed to be the position of the dipper at the beginning of the digging movement; position B at the end of 40 the digging movement; position C elevated dumping position with the dipper extended; and position D, which shows the dipper in full lines, retracted position. If the machine is being used in an open space or in 45 a wide confined space, the turn-table may be revolved with the dipper in position C, but if it is operating in a narrow space, as in a mine drift or tunnel, the dipper will be swung back to position D before the superstructure is revolved, and then the dipper 50 may be extended to dump the contents in a car or receptacle at the rear of the machine. When in position C the dipper may dump at the side as well as at the rear. The approximate parallelogram relation of arms 55 21 and cables 24 is important when the dipper is being swung from positions C to D, or from D to C, for the reason that in swinging the dipper from either of these 60 positions to the other, it is unnecessary to wind in or pay out the cables 24, and during such movement the operator need pay no attention to the drums 25. On the other hand, if the axis of rotation of the swinging 65 arms 21 coincided more or less with the axis

of the drums it would be necessary to rotate the drums as well as the arms to keep the dipper in the desired position to retain the material therein in swinging the dipper from one position to the other. It is not essential that the portions of the cables extending between the drums and the dipper arm extensions 23 be parallel with the arms 21, in all positions of the latter, for a slight deviation, such as in the present machine, 70 from a true parallelogram arrangement of the parts does not cause a material change in the inclination of the dipper in moving it from position C to position D, or from D to C. 75

Power for swinging the arms 21, for swinging the arms 19, for turning the superstructure and for propelling the machine over the ground is in this case derived from a single motor 27, which may be of any 80 suitable type. This motor is in this instance supported on cross members 28 (see Fig. 6) extending between the side housings 10^a and at the forward end of its rotary shaft it is provided with a pinion 29 engaging a relatively large gear 30 on a short shaft 31, which shaft is provided also with a sprocket wheel 32 and a bevel pinion 33. 85

Forwardly of the motor and above shaft 31, are two shafts 34 and 35, the former being utilized to swing the arms 21 and the latter to turn the superstructure and also to propel the machine. The shaft 34 is provided with a gear 36, which engages the large gear 30 and is driven by it. This 90 shaft is in alignment with a shaft 37 provided with a worm 38 engaging a worm wheel segment 39 secured to cross shaft 22, which operates the swinging arms. The shaft 34 is adapted to drive the worm 95 shaft 37 either direct or through a reversing gear, and in this instance a common form of reversing gear is shown in Fig. 4. This includes a drum 40 adapted to be held stationary by a brake band 41 (see Figs. 4 and 100 5) or to be clutched to the shaft by a movable clutch member 42, this drum having studs carrying pinions 43 engaging an internal gear 44 carried by the shaft 37 and also engaging a pinion 45 keyed to the shaft 105 34. When the drum 40 is clutched to the shaft 34, the pinions 43 do not rotate on their respective axes, hence the whole reversing gear rotates as a unit, and the shaft 34 drives the shaft 37 direct. On the other 110 hand, when the drum is unclutched from the shaft and is held stationary by the brake band 41, the shaft 34 drives the shaft 37 in the reverse direction and at a reduced speed through the pinion 45, pinions 43, and internal gear 44. This mechanism, controllable by the operator when occupying the operator's station or seat 46, thereby provides for the swinging movements of arms 21 in both 115 directions. 120

The drum shaft 26 is required to be driven by power in one direction only. This is provided by the following mechanism: The bevel gear 33 on the short lower shaft 5 31 engages a relatively large bevel gear 47 which is normally loose on the drum shaft 26, but is adapted to be clutched thereto by a movable clutch member 48. This provides for rotation of the drum shaft to wind 10 in the cables 24, to swing the dipper arms outwardly. The latter are swung inwardly by gravity which requires the paying out of the cables 24. This paying out of the cables is controlled by the operator by the 15 following mechanism: Keyed or otherwise secured to the drum shaft 26 is a ratchet wheel 49 (see Figs. 4 and 5) which when the cables are being wound in, rides freely under pawls 50 carried by a drum 51 adapted to rotate on an extension of the bearing 20 for shaft 26, the drum being normally held from rotation by a brake band 52, (see particularly Fig. 4) which brake band can be loosened or released from the drum by a 25 suitable operating member 53 controllable by the operator when occupying his seat 46. When the brake band is tight on the drum, the drum shaft is held against reverse rotation, but when the brake band is released, 30 the cables can pay out at a rate controllable by the operator. This mechanism therefore provides for inward movement of the dipper arms and for swinging the arms out under power for a filling stroke as in moving the dipper from position A to position 35 B, or from position B upwardly. While the dipper is being filled by thus swinging the dipper arms 19, the swinging arms 21 can be held stationary, or they can be raised and lowered as desired, with the result that 40 the dipper can be swung through an arc of a circle in filling, or it can be given a substantially horizontal filling movement, or a combination of these movements.

45 As previously stated, the shaft 35 is utilized to swing the turn-table in either direction. To accomplish this, this shaft is provided with two bevel gears 54, each of which is adapted to be clutched to the shaft by a movable clutch member 55. These bevel gears engage a bevel gear 56 on a vertical shaft 57 suitably supported in bearings on the turn-table, this shaft being provided at its lower end with a pinion 58, engaging gear 59, which is just beneath the turn-table base and surrounds the shaft 15 about which the turn-table is adapted to turn (see particularly Fig. 6). Obviously if gear 59 is held from rotation, the turn-table, and, in fact, the entire superstructure will rotate about the axis of the shaft 15, when the pinion is rotated, the direction of rotation depending, of course, upon the direction of rotation of shaft 57 and pinion 58.

60 65 This mechanism therefore provides for

the rotation of the superstructure to permit a loaded dipper to be swung to dumping position and back again for another load. It is also utilized for propelling the machine over the ground, and to do this the following additional mechanism is provided. The gear 59 is held stationary only when the superstructure is to be rotated, but is also intended to be rotated and to transmit power to the driving shaft for the endless belts 12. 70 Gear 59 is therefore provided on its lower side with a bevel gear 60 which meshes with a bevel gear 61 keyed to a horizontal shaft 62 carried by the truck frame 11, this shaft having at its rear end a bevel gear 63 engaging a bevel gear 64 (see Fig. 2), which bevel gear is on a shaft which is adapted to be clutched to and unclutched from the rear or driving sprockets 65 in the well-known manner. 80

85 Additionally I provide means for holding the gear 59 against rotation as when the superstructure is to be rotated, and for releasing the gear so that it may rotate under the action of the pinion 58 to propel the machine. This is preferably in the form of a laterally movable latch 66 (see Figs. 1, 2, 5, 7 and 8) which latch engages guides 66a (see Fig. 8), and is provided at its inner end with an inclined locking tooth 67, adapted to be moved inward between any two adjacent teeth of bevel gear 60. This latch is supported by the truck frame, and when retracted, it receives between two projections 68 the end of a pawl 69 carried by the turn-table, and thus holds the superstructure from rotation. That is to say, when the latch is in its innermost position it holds the gears 59 and 60 against rotation to permit the superstructure to be revolved, and when the latch is retracted, the gears are released so that they may rotate and thus transmit power to the running gear or propelling mechanism of the truck, and when it is pulled outward or retracted, it receives the 100 pawl 69 which locks the superstructure against rotation.

105 All essential movements of the machine are controlled by the operator, when occupying the seat or station 46, through hand levers 70, indicated in Fig. 2. By these instrumentalities the shaft 22 and the swinging arms 21 can be rocked in either direction, the drum shaft 26 can be rotated under power to swing the dipper and dipper arms in one direction, and it can be released by movement of the brake band controlling the drum 51 to permit the rotation in the reverse direction, the superstructure can be rotated in either direction, and the brake 115 band 41 controlling the reversing gear for shaft 22 can be actuated. Additionally, of course, the same levers which control the rotation of the turntable are utilized to control the forward and rear propulsion of 120 125 130

the machine as a whole over the ground, the latch 66 being moved in and out to permit the motor to perform either function.

- Assuming that the dipper is in position A, 5 to fill the dipper the drum shaft is rotated to wind in the cables 24 so as to swing the dipper forwardly or forwardly and upwardly, the arms 21 being at the same time moved downward if a practically horizontal 10 filling motion of the dipper is desired. After the dipper is filled it is swung to substantially position C by rotating the arms 21, and to some extent also, the dipper arms. If the machine is operating in a wide space, 15 the superstructure can be rotated with the dipper extended, but if the machine is working in a narrow space, the dipper will be retracted to substantially position D, and this is done, as already explained, without 20 the necessity of the drum shaft rotating in either direction. Then after the rotation of the superstructure, the dipper will again be extended and dumped, this being followed by reversal of the movements explained. 25 The dipper has a considerable reach, and the material can be gathered up cleanly over considerable space to the sides as well as in front of the machine. Additionally the machine is easily controlled, and the construction which permits of a single motor 30 performing all the necessary functions or movements is an important feature of the invention.

Having described my invention, I claim:

- 35 1. In a loading machine, a traveling base, a revoluble superstructure mounted thereon, digging mechanism carried by the superstructure comprising a digging member, an arm attached thereto, a second arm connected to the first named arm and supported for swinging movement on a part of the superstructure, a power operated device for swinging the second mentioned swinging arm, a second power operated device, and 40 means connecting it to the first named arm, the connecting means being displaced from and having a substantially parallel relation with the second mentioned arm, whereby said elements have substantially the function 45 of two opposite members of a parallelogram of forces during a portion of the cycle of movement of the digging mechanism.
2. In a loading machine, a traveling base, a superstructure mounted thereon and comprising a turn-table and digging mechanism including a dipper having a dipper arm connected therewith, a dipper swinging arm mounted on the turn-table for movement about a given axis, a drum rotatable about 50 a different axis and having a cable connection with the dipper arm, and separately controlled power devices for operating the dipper swinging arm and drum.
3. In a loading machine, a traveling base, 55 a revoluble superstructure mounted thereon comprising a turn-table and a digging member in the form of a dipper with a dipper arm attached thereto, a dipper swinging arm mounted for rotary movement on the turn-table about a given axis, a drum shaft 60 mounted for rotary movement about an axis displaced from the first named axis and provided with a drum having a cable connection with an extension of the dipper arm, and separately controlled power devices for turning said dipper swinging arm and for rotating said shaft.

including a turn-table and a digging member in the form of a dipper with a dipper arm attached thereto, a dipper swinging arm mounted for rotary movement on the turn-table about a given axis, a drum shaft 70 mounted for rotary movement about an axis displaced from the first named axis and provided with a drum having a cable connection with an extension of the dipper arm, and separately controlled power devices for turning said dipper swinging arm and for rotating said shaft.

4. In a loading machine, a traveling base carrying a revoluble superstructure comprising a turn-table and a digging member 80 in the form of a dipper having an arm attached thereto, a dipper swinging arm rotatably supported by the turn-table and pivotally connected to the dipper arm between its ends, a drum supported by the turn-table 85 and having a cable connection with the inner end of the dipper arm, and separately controlled power devices for turning said dipper swinging arm and for rotating the drum.

5. In a loading machine, a traveling base 90 carrying a revoluble superstructure comprising a turn-table and a digging member in the form of a dipper having an arm attached thereto, a dipper swinging arm rotatably supported by the turn-table and pivotally connected to the dipper arm, a drum supported by the turn-table and having a cable connection with the dipper arm, power 95 operated means for rotating the dipper swinging arm in opposite directions, and power operated means for rotating the drum in one direction.

6. In a loading machine, a traveling base, a revoluble superstructure mounted thereon and comprising a turn-table and a digging 100 dipper, a pair of parallel shafts carried by the turn-table, an arm on one of said shafts, a drum on the second shaft, a second arm connected to the digging member and pivotally connected to the outer end of said 110 first named arm, and a cable between the drum and the dipper arm having a substantially parallel relation with the first mentioned arm.

7. In a loading machine, a traveling base, 115 a revoluble superstructure mounted thereon and comprising a turn-table and a digging dipper, a pair of parallel shafts carried by the turn-table, an arm on one of said shafts, a drum on the second shaft, a second arm connected to the digging member and pivotally connected to the outer end of said 120 first named arm, and a cable between the drum and the second arm, and a motor with connections for rotating one shaft in both directions and the other shaft in one direction.

8. In a loading machine, a traveling base, 125 a revoluble superstructure mounted thereon and comprising a turn-table and a digging

dipper, a pair of parallel shafts carried by the turn-table, a dipper swinging arm on one of said shafts, a drum on the other shaft, a dipper arm connected to the dipper and pivotally connected to the first named arm, a cable between the drum and the dipper arm, a motor with connections for rotating one shaft in both directions and the other shaft in one direction, and means for permitting a controlled rotation of the last mentioned shaft in the reverse direction.

9. In a loading machine, a traveling base, a revolute superstructure thereon comprising a turn-table and digging mechanism including a dipper with a dipper arm and a dipper swinging arm supported by the turn-table and connected to the dipper arm, and a power operated shaft connected to the dipper swinging arm through a reversing gear which permits the power operated shaft while rotating in the same direction to swing said arm in both directions.

10. In a loading machine, a traveling base, a revolute superstructure mounted thereon including a turn-table having a digging mechanism including a dipper with a dipper arm and a dipper swinging arm mounted for swinging movement on the turn-table and pivotally connected to the dipper arm, power means for actuating the swinging arm, a drum shaft having a cable connection with the dipper arm, a power operated shaft for rotating the drum in one direction and adapted to be clutched to and unclutched from said drum shaft, and means including a brake device for holding the drum shaft against rotation when the clutch is disengaged and for permitting a controlled rotation in the reverse direction.

40 11. In a loading machine, a traveling base, a revolute superstructure mounted thereon, including a turn-table, a digging

member, inner and outer arm connected together and connected to the turn-table and digging members for supporting and operating the latter, means for swinging the inner arm and means for swinging the outer arm comprising a drum shaft on the turn-table having a cable connection with the outer arm, power means adapted to be clutched to and unclutched from the drum shaft for rotating the latter in one direction, and co-operating members which permit rotation of the drum shaft in one direction and normally prevent rotation in the reverse direction but permit a controlled rotation in the last mentioned direction.

12. In a loading machine, a traveling base, a revolute superstructure mounted thereon, including a turn-table, a digging member, inner and outer arms connected together and connected to the turn-table and digging members for supporting and operating the latter, means for swinging the inner arm and means for swinging the outer arm comprising a drum shaft on the turn-table having a cable connection with the outer arm, power means adapted to be clutched to and unclutched from the drum shaft for rotating the latter in one direction, and means for holding the drum shaft against rotation when unclutched from the power means and for permitting a controlled rotation in the reverse direction comprising two co-operating members, one secured to the drum shaft and free to rotate with respect to the other in one direction, and the other normally stationary and adapted to rotate to permit the rotation in the reverse direction.

80 In testimony whereof, I hereunto affix my signature.

ROBERT P. GREENLEAF.
